UNITED STATES PATENT OFFICE

DONALD G. SMELLIE, OF CANTON, OHIO, ASSIGNOR TO THE HOOVER COMPANY, A CORPORATION OF OHIO

SUCTION CLEANER AGITATOR

Application filed November 18, 1929. Serial No. 407,849.

This invention relates to improvements in suction cleaner rotors or agitators and has for its principal object the provision of a new and improved agitator of light weight which is structurally strong and commercially feasible. A further object is the provision of an agitator for a suction cleaner in which the agitating elements are formed in the surface of the agitator. A still further object is the provision of an agitator in which the sweeping members extend closely adjacent and parallel to the beating elements. Other objects will appear as the description proceeds.

Referring to the drawing in which is illustrated a preferred embodiment of the invention and in which the same reference character identifies the same part in the various views:

Figure 1 is a side view of an agitator constructed in accordance with my invention with part of the metallic covering broken away.

Figure 2 is a cross section upon the line 2-2 of Figure 1.

The agitator, indicated by the reference character 1, constructed in accordance with the present invention comprises a cylindrical core member 2 of wood or other similar relatively light, strong and inexpensive material, which extends the entire length of the agitator. A portion 3 of core 2 defined by the converging walls, one of which is indicated by the reference character 4, near the approximate longitudinal center thereof, has a reduced diameter and serves as a belt-receiving pulley for the reception of a rotating torque for the agitator. Extending helically around the core member 2 from the opposite ends thereof and in opposite directions of angular advance are the brush-receiving grooves 5, 5 which are spaced 180° apart circumferentially. Positioned within the grooves 5, 5 are sweeping brushes 6, 6 including backs 7, 7 which are held in any suitable manner.

Enclosing and closely surrounding the core member 2 are metallic sheaths or coverings 8, 8 held in position on the member 1 by retaining lips 9, 9 tightly compressed along the side walls of the helical grooves 5, 5 and by the inner walls 11, 11 swaged adjacent the

walls 4, 4 of the pulley 3. At the ends of the grooves 5, 5 the sides of the individual coverings 8, 8 make line contact as at 10, 10.

Formed in each covering 8 are the semi-cylindrical extrusions 12, 12 forming beater elements which extend helically in opposite directions of angular advance from a common end point at each end of the member 1. With the sheaths 8, 8 positioned upon the member 2 with the lips 9, 9 against the walls of the grooves 5, 5 the extrusions 12, 12 upon the opposite sides of the pulley 3 are continuous and form, in effect, two beater elements upon the surface of the agitator extending the entire length thereof, the pulley width being excepted, and having common end points. In the assembled relation of the agitator one of the beater elements 12 upon each side of the pulley extends parallel to the brush-receiving groove 5 upon that side, said groove 5 being positioned outside of the included angle made by the converging elements 12, 12. Formed at the inner ends of the coverings 8, 8 and extruded a distance equal to beater elements 12, 12 are carpet spacer elements 13, 13 extending around the entire circumference of the core 2. The extruded elements 12, 12 and 13, 13 may be formed in any suitable manner before the coverings 8, 8 are placed on the core 2 after which the inner ends 11, 11 of said coverings may be swaged adjacent the walls 4, 4 of pulley 3 and the lips 9, 9 secured in place.

Fitted upon the ends of the agitator body and assisting to maintain the sheaths 8, 8 in close relation to the core 2 are the metallic caps 14, 14. The caps 14, 14 function further to protect the wooden core 2 at its ends and to provide means whereby suitable supporting means for the agitator body may be connected.

From the foregoing it is clear that a simple construction has been provided which is light in weight and economical in manufacturing costs yet which comprises the elements necessary for an efficient rotary suction cleaner agitator. The provision of the wooden core for the agitator makes possible the construction of the enclosing metallic shell of thinner material than would otherwise be

possible, and the forming of beater elements in the body of the enclosing sheath makes possible a still further economy. The positioning of the sweeping brush adjacent the beater bar insures the sweeping of the surface covering as it recovers from the impact of the beater which results in increased cleaning efficiency and long brush life. The cylindrical spacing elements included in the construction function to prevent the surface covering being displaced into contact with the rotor body adjacent the pulley by the lifting effect of the suction within the suction nozzle within which the agitator is carried resulting in a desirable reduction in the power necessary to drive the agitator.

I claim:

1. An agitator comprising a cylindrical body-member having a helical groove therein forming a brush seat, a brush positioned therein, inwardly extending walls connected by an uninterrupted surface at their bases on said body, forming a pulley, a metallic covering encircling said body helical semi-cylindrical extrusions thereon forming beater elements extending longitudinally thereof, integral fastening means formed in said covering and securing said covering to said body and end caps upon said body.
2. An agitator comprising a cylindrical body-member having a helical groove therein forming a brush seat, a brush positioned therein, a metallic covering encircling said body, oppositely curved helical beater elements on said covering extending longitudinally thereof and fastening means securing said covering to said body.
3. An agitator comprising a cylindrical body having a helical groove therein forming a brush seat, a brush positioned therein, a metallic covering encircling said body and a helical beater element thereon extending parallel to said groove.
4. In an agitator for suction cleaners, a cylindrical body-member, a helical groove in said body-member forming a brush seat, a brush positioned therein and a metallic covering having a beater element thereon enclosing said body-member.
5. In an agitator for suction cleaners, a body, beater means positioned on said body, a brush carried by said body characterized by the fact that the brush extends parallel to and closely adjacent said beater means.
6. In an agitator for a suction cleaner, a cylindrical body, beater bars thereon extending radially beyond the surface of said body, a pulley adapted to receive a belt and positioned between the ends of said body, and smooth raised portions of substantially the height of said beater bars adjacent the sides of said pulley forming carpet spacers.
7. A suction cleaner rotary agitator comprising a central wooden core, a metallic surface-contacting covering surrounding said

core, a pulley formed between the ends of said agitator positioned radially within the periphery thereof, and a surface-contacting brush carried by said core extended thru said metallic covering.

Signed at North Canton, in the county of Stark, and State of Ohio, this 8th day of November, A. D. 1929.

DONALD G. SMELLIE.
